Manufacturing Co., Kansas City, Mo., a corpora-
tion of Missouri

Application February 17, 1939, Serial No. 256,904

11 Claims. (Cl. 62—19)

Our invention relates to refrigeration insulation, and more particularly to the structure of the insulated walls of a refrigerated space.

It is common to insulate refrigerated spaces by enclosing them in double walls, comprising an inner wall positioned in spaced relation to an outer wall, with the inter-wall space filled with heat insulating material, such as ground cork, balsam wood, rock wool, glass wool, kapok and the like. It was soon observed that the insulating material became impregnated with moisture, greatly lessening its heat insulating qualities. Frequently the accumulations of moisture would rot those insulations comprising derivatives of wood or organic material.

Attempts have been made to seal the insulating material in water-proof envelopes. It has been found, however, that this is ineffective since envelopes which are water-proof are not vapor proof. That portion of the envelope which contacts the cold wall will be chilled below the dew point, causing a precipitation of moisture and lowering the vapor pressure. Vapor at higher vapor pressure will pass through the water-proofing and condense against the cold wall, with the result that moisture will collect in the insulation. It is so difficult to render a wall vapor proof as to be substantially commercially unfeasible.

Prior attempts to solve the problem of providing an insulating wall construction for refrigerated spaces have proceeded on the theory that there was "breathing," due to barometric and temperature changes. Provision was made to permit breathing from the cold side. This proved to be generally ineffective. Our research has shown us that vapor will pass through the outer wall and insulating material to the cold wall or cold side in almost straight lines. The resistance to flow of vapors through the insulating material so reduces their velocity that before they can escape from the insulation, they are condensed adjacent the cold side by being chilled below their dew point. Once moisture is precipitated, it further reduces the velocity of flow of the vapors through the insulating material, with the result that the condensation of vapors in the insulation continues progressively, becoming rapidly worse as the insulation becomes saturated with moisture.

We have determined that it is possible to insulate a refrigerated space and maintain the insulation in substantially dry condition. We have solved the problem by permitting the vapors to flow through the insulation out of contact with

a condensing surface at a sufficient velocity to prevent their condensation within the inter-wall space.

One object of our invention is to provide an insulated wall construction for refrigerated spaces.

Another object of our invention is to provide an insulated refrigerator car for railway use in which the insulation will be maintained in a substantially dry state over extensive periods of time.

A further object of our invention is to provide a novel insulated drip pan construction for refrigerator cars.

Other and further objects of our invention will appear from the following description.

15 In the accompanying drawings which form part of the instant specification, and which are to be read in conjunction therewith, and in which like reference numerals are used to indicate like parts in the various views:

20 Fig. 1 is a sectional view of the end of a refrigerator car showing our novel drip pan construction which embodies the principles of our wall construction.

Fig. 2 is an enlarged sectional fragmentary view of a wall construction showing one mode of carrying out our invention.

Fig. 3 is a sectional view of a wall construction showing another embodiment of our invention.

Fig. 4 is an enlarged fragmentary sectional view of the drain of the drip pan construction shown in Fig. 1.

Fig. 5 is a sectional view with parts broken away, of a refrigerator car showing another embodiment of our invention.

35 In general, our invention contemplates the provision of a pair of walls spacedly positioned from each other to define an inter-wall space. One wall forms the boundary wall of the refrigerated chamber. The outer wall is in contact

40 with warm air. Positioned between the walls we provide heat insulating material of any suitable type. The heat insulating material, however, must be such that it will offer minimum resistance to the passage of the vapors. The insulation between the walls is not permitted to contact

45 the cold wall, that is, the inner wall adjacent the refrigerated space. We have found that if the insulating material contacts, or is closely adjacent to the cold wall, vapors will condense upon

50 the cold wall before they can escape from the inter-wall space. The space formed by the inner surface of the insulating material is vented to the space of lower vapor pressure. Inasmuch as there is no insulation material in the space communicating with the vents, the passage of vapors

from this space through the vents into the space of lower vapor pressure is sufficiently rapid to prevent the condensation of vapors until they have escaped into the cold space of lower vapor pressure. We have found there is a definite relationship between the rate of vapor penetration and the venting area. If we permitted the free passage of vapors into the insulating material, a large venting area would be necessary in order to preclude condensation within the inter-wall space. In order to be able to use a smaller venting area, we seal the warm side of the insulation with any suitable waterproof material. As indicated above, we have been able to find no material which will prevent the passage of vapors. The sealing of the warm side by a water-proof material such as sheet rubber, asphalt or tar impregnated cloth or paper, pitch, and the like, however, will reduce the flow of vapors into the insulation enabling us to insure the removal of these vapors from the insulating material rapidly with the use of a reduced venting area. We have found, furthermore, that even in cases where the insulating material is initially moistened, that our construction will enable the moisture to be evaporated from the insulation so that it will ultimately become dry.

The provision of means communicating with a space of lower vapor pressure to the space adjacent the insulation, that is, between the surface of the insulating material and the cold wall, will insure the evaporation of such moisture as may be present in the insulation. If the insulation is of such character that it does not present a too great resistance to vapor flow, the communication of the insulation with the zone of lower vapor pressure will effect the evaporation of any free moisture initially present.

We have found that an insulating material made of fibres of glass is excellent for use in our invention, inasmuch as this material appears to present a decreased resistance to the flow. This enables the vapors to pass quickly into the insulation-free space adjacent the cold wall for condensation within the cold space. If the passage of vapors is impeded condensation will take place upon the outside of the cold wall, with the result that moisture may drip or run onto the insulation. If this condition exists, the vapor velocity will be too small to effectively evaporate the moisture, and the insulation will become gradually saturated with moisture.

More particularly, referring now to the drawings, Fig. 1 discloses a fragmentary sectional view of one end of a refrigerator car, showing the usual ice bunker 1. Ordinarily the temperatures within the refrigerator car are not sufficiently low to present a severe problem, and the refrigerator car is shown with an outer wall 2, and an inner wall 3, between which, secured in any suitable manner, is an insulating blanket 4. The inner wall 3 is usually at a temperature sufficiently high that vapors may escape from the insulating blanket 4 without condensing therein. In order to insure that this takes place, we have sealed the warm side of the insulation blanket, which is adjacent the ice bunker, with a layer of sealing material 5. As the ice melts, the water, at temperatures in the vicinity of 32° F., will drip into a drip pan 6. The surface of the drip pan will be sufficiently cold so that vapors will condense rapidly within the insulation outboard of the drip pan in the usual construction.

It will be noted that in the region of the drip pan we have provided insulating material 7, the

warm side of which is sealed by sealing material 8. The insulation 7 is spaced from the cold drip pan 6 and does not contact it. This provides a free space 9 between the cold wall and the insulation 7. The space 9 is vented by a plurality of vents 10, each fitted with caps 11 to prevent the passage of moisture into the insulated space. The insulation is such that the vapors will pass freely through the insulation 7, it being of a character which presents a reduced impedance to vapor flow, such as glass wool or the like. The resistance to vapor flow in the space 9 is exceedingly small. This space is vented by the plurality of vents 10. As the vapor leaves the insulating material 7, it is not in contact with anything sufficiently cold to condense it. When the vapor does contact a cold surface it is flowing at a sufficient velocity so that condensation will not take place until the vapor has escaped into the cold compartment where condensation will ultimately take place by contact with the refrigerating medium, which may be ice or expansion coils connected to suitable refrigerating apparatus.

The remainder of the car shown in Fig. 1 is provided with the customary insulating blanket 12, as the temperature of the cold wall 13 is not sufficiently low to condense vapors severely.

In the embodiment just described, it will be observed that this specific embodiment of our invention has been applied only to that portion of the refrigerator car which presents surface sufficiently cold to cause rapid condensation of vapors within the insulation. This construction need not be employed for the remainder of the car in this case because the velocity of vapor flow through the inner wooden side walls 3 is sufficiently great for the temperatures involved to insure that condensation will not take place if the warm side is sealed. It will be understood that the construction shown in Fig. 1 for the side wall adjacent the ice bunker may be employed in many cases where the vapor pressure on the cold side is not too low. It will be further observed that the wooden wall is a permeable one which is in effect venting the insulation over its entire cold surface. If the wall is sufficiently permeable and the warm side is sealed, the principles of our invention operate and the insulation will remain dry.

Fig. 2 shows a fragmentary sectional view of a wall designed to be employed for spaces refrigerated to a low temperature, such as cold storage spaces and the like. The outer wall is indicated at 14 and the inner wall at 15. Insulation 16 is secured in any suitable manner to the outer or warm wall 14. The warm side of the insulation is sealed by a layer of material 17. The upper surface 18 of the insulation 16 is spaced from the cold wall 15, providing a space 19. The cold wall 15 is provided with a plurality of vents 20 fitted with cap members 21. The arrows in Fig. 2 show the direction of vapor flow from the space of high vapor pressure to the space of lower vapor pressure. The insulation 16 is of the type which will present a predetermined minimum resistance to the flow of vapors. The venting area may be determined empirically and is a function of the effectiveness of the sealing layer 17 as a vapor barrier, the difference in vapor pressure between the refrigerated space and the space without and the resistance to flow of vapors through the insulating material 16. The wall structure may be so designed that the venting area will be sufficient to permit a rapid flow of

vapors from the space 19 out through the vent and into the space of lower vapor pressure.

Due to the fact that there is an unobstructed space between the cold wall and the upper surface 18 of the insulation 16, the flow of vapors escaping from the insulation will be directly to the vents and out into the cold space.

Referring now to Fig. 3, we have shown another embodiment of our invention, in which the insulation 16 is placed against the warm wall 14 and spaced from the cold wall 15. We provide an auxiliary wall 22 spaced from the cold wall 15. The wall 22 will be at a temperature sufficiently high so that vapors contacting it will not condense. A plurality of vents 23 are provided through the wall 22 into the space 24 between the wall 22 and the cold wall 15. The vents 23 are provided with cover members 25. The space 24 is provided with vent pipes 26 leading to the refrigerated space of lower vapor pressure, to which the vapors pass for condensation. Due to the fact that the space 24 is unobstructed, vapors will readily flow to the vents. The insulation 16 is sealed at its warm side by a sealing layer 17. The sealing layer reduces the passage of vapors into the insulation but, as pointed out hereinabove, will not prevent vapor passage. After the vapors pass the barrier 17, they will flow through the insulation 16 which is of such character as to present a reduced resistance to vapor flow. The wall surface 22 is not sufficiently cold to cause condensation so that the vapors will escape in the vapor phase into the unobstructed space 24 formed by the wall 22 and the wall 15, and flow out through the vents 26. When the construction is used in refrigerator cars we may provide valves 27 in the vent pipes 26.

In the winter season refrigerator cars are sometimes operated in heating service. During such use heating means are provided instead of cooling means in the ice bunkers. When refrigerator cars are operated in heating service, the valves 27 are closed. The difference in vapor pressure between the inside of the car and that in the space 24 is usually sufficiently low when refrigerator cars are operated in heating service that there is no problem of passage of vapors through the wall 15.

Referring now to Fig. 4, the bottom of the drip pan 6 may be covered with a water-proof layer 28, which may be pitch, rubber, or the like. Water from melting ice passes into sumps 29. The sumps and drain pipes 30 may be made out of non-metallic material, such as phenol condensation products, hard rubber or the like. A cap member 31 is fitted over the drain pipe forming a trap and providing a water seal between the outside air and the interior of the ice bunker. A water-proof sleeve 32, which may be made out of rubber or any other suitable material, seals the insulation 7 from contact with the drain pipes 30. Any condensation on the outside of the drain pipes will therefore not affect the insulation.

Referring now to Fig. 5, we have shown a refrigerator car fitted with one embodiment of our invention. Refrigerator cars pass through many climatic conditions and are subjected frequently to severe tests for the insulation. With some perishable commodities, snow formed from ice is blown into the refrigerator car to act as a refrigerating medium.

While our invention may be applied to insulate any refrigerated space, and the principles remain the same, we have shown it with respect to a refrigerator car for purposes of illustration only.

It will be noted that we provided insulation 33 completely around the space to be refrigerated. The insulation is placed adjacent the warm wall, that is, the outside wall of the car. A sealing layer 34 seals the warm side of the insulation. The insulation itself is spaced from the inside walls 35 and the bottom wall or floor 36, and from the ceiling 37, providing a space 38 formed by the cold wall and the inside surface of the insulation 33. The insulation is of the character which will present a minimum resistance to vapor flow. The unobstructed space 38 is vented into the cold space through a plurality of vents 39. Under the ice bunker 1 we provide the drip pan 6, covered with water-proofing material 28. It will be noted that the floor of the car, 36, is likewise covered with a water-proof layer 40. Due to the fact that the drip pan 6 is colder than any other interior wall of the refrigerator car, we provide the vents 10, provided with cap members 11, in the region of the drip pan, to provide for the rapid venting of vapors from the space 38 immediately below the drip pan 6.

It will be apparent from the foregoing that the construction shown in Fig. 5 will insulate the refrigerator car and preclude the condensation of vapors in the insulation, thus maintaining it dry and of unimpaired efficiency.

Referring again to Fig. 1, it will be noted that the transverse structural member 50 supports a vertical portion of the sealing means 8, which seals the warm side of the insulation 7. The sealing means in the transverse structural member 50 provides a water-proof barrier separating the insulation 7 underneath the drip pan 6 and the main insulation blanket 12 of the main car body.

It will be understood, of course, that in the instant invention the object of the sealing means 8 is to prevent the migration of vapors into the insulation 7. The barrier just described has another important purpose. Occasionally the drain opening may become clogged, permitting the accumulation of water from the melted ice in the drip pan. Motion of the car may cause this water to overflow through the vents onto the insulation, thus wetting it. Sometimes corrosion of the drip pan may occur, permitting leakage into the insulation.

In event of accidental overflow of moisture due to clogging of the drip pan drain, our construction is such that the moisture will ultimately be dried due to the venting to the space of lower vapor pressure. If our vents become clogged, condensation will then take place against the cold surface since the space above the insulation is not in communication with the space of lower vapor pressure. In such case condensation upon the outer cold side of the drip pan will cause moisture to drip onto the insulation.

The remaining portion of the car, however, has the customary insulation 12, and should this become wet it will remain wet, thus impairing its efficiency. The water-proof barrier 50 will prevent migration of such moisture, as will accidentally accumulate in the insulation 7, along the insulation situated under the remaining body of the car. This insulation is customarily in the form of blankets which are stitched for ease in handling. The stitching forms actual troughs or channels along which the moisture may flow. Then, too, moisture may pass to the remaining insulation by capillary action, were it not for the barrier which we provide.

It will be seen that we have accomplished the

objects of our invention. We have provided an insulating wall construction for refrigerated spaces in which we are able to preclude the condensation of vapors in the insulating material. We have provided a drip pan construction which may be used on existing refrigerator cars to prevent the break down of the insulation at the trouble spot.

It will be understood that certain features and sub-combinations are of utility and may be employed without reference to other features and sub-combinations. This is contemplated by and is within the scope of our claims. It is further obvious that various changes may be made in details within the scope of our claims without departing from the spirit of our invention. It is, therefore, to be understood that our invention is not to be limited to the specific details shown and described.

Having thus described our invention, we claim:

1. An insulated wall construction for refrigerated spaces including in combination, an inner wall forming a boundary for the refrigerated space, an outer wall spaced from said inner wall, fibrous heat insulating material positioned in the inter-wall space adjacent the outer wall having a surface spaced from the inner wall and forming a passageway therewith, sealing means for said insulation adjacent the outer wall, and means providing communication between said passageway and the space being refrigerated.

2. A wall construction for refrigerated spaces including in combination a cold wall forming a boundary for the refrigerated space, a warm wall spacedly positioned from said cold wall, fibrous heat insulating material located in said inter-wall space adjacent the warm wall having a surface spaced from said cold wall and forming a passageway therewith, said insulating material being of such character as to permit the ready passage of vapors therethrough, means for sealing said insulation adjacent the warm wall, and means providing communication between said passageway and the space being refrigerated.

3. A drip pan construction for refrigerator cars including in combination a drip pan adapted to be positioned under the ice bunker of the refrigerator car, insulation positioned below said drip pan and spaced therefrom to form a passageway therewith, and means for venting said passageway into said ice bunker.

4. In a drip pan construction for a refrigerated space having an ice bunker and a drip pan, insulation spaced below the drip pan to form a passageway therewith, means for sealing the lower side of said insulation, and means for providing communication between said passageway and the refrigerated space.

5. In a refrigerator car having an ice bunker and a drip pan, heat insulating material permitting the ready flow of vapors therethrough spacedly positioned below the drip pan and forming a passageway therewith, means for sealing the surface of the insulation remote from said drip pan,

a drain pipe for said drip pan passing through said insulation, means for sealing said drain pipe from said insulation, a water seal for said drain pipe, and means providing communication between said passageway and the interior of the refrigerator car.

6. A wall construction for a refrigerated space including in combination a cold wall forming a boundary for the refrigerated space, an outer wall spacedly positioned from said cold wall, a third wall intermediate said cold wall and said outer wall, fibrous heat insulating material positioned between said third wall and said outer wall, sealing means for said insulation adjacent said outer wall, said third wall being spacedly positioned from said cold wall and forming a passageway therewith, means providing communication between said insulation and said passageway, and means providing communication between said passageway and the space being refrigerated.

7. A wall construction as in claim 6 in which said heat insulating material permits the ready passage of vapors therethrough.

8. In an insulated wall construction for refrigerated spaces, an inner cold wall, said wall being made of permeable material, an outer warm wall spacedly positioned from the cold wall, fibrous heat insulating material in the inter-wall space, and means for sealing said insulation adjacent the outer warm wall.

9. A wall construction for a refrigerated space including in combination a cold wall forming a boundary for the refrigerated space, an outer wall spacedly positioned from said cold wall, a third wall intermediate said cold wall and said outer wall, fibrous heat insulating material positioned between the third wall and said outer wall, means for sealing said insulation adjacent said outer wall, and means for providing communication between said insulation and the passageway formed by said cold wall and said third wall.

10. In a refrigerator car having an ice bunker and a main body, a drip pan under said ice bunker, insulation under said drip pan and insulation under said main body, and a waterproof barrier between said insulations.

11. A wall construction for a refrigerated space including in combination a cold wall forming a boundary for the refrigerated space, an outer wall spacedly positioned from said cold wall, a third wall intermediate said cold wall and said outer wall, heat insulating material positioned between said third wall and said outer wall, said third wall being spacedly positioned from said cold wall and forming a passageway therewith, means providing communication between said insulation and said passageway, means providing communication between said passageway and the space being refrigerated, and a valve for said means providing communication between said passageway and the refrigerated space.

ALBERT L. GUSTIN, JR.
JAY O. BRELSFORD.
